OPERATING VALVE

Filed Jan. 16, 1947

UNITED STATES PATENT OFFICE

2,589,794

OPERATING VALVE

Virgil L. Frantz, Roanoke, Va.

Application January 16, 1947, Serial No. 722,383

11 Claims. (Cl. 137—69)

1

This invention pertains to an operating valve and more particularly to a type thereof adapted for use in a sanding mechanism of a railway locomotive.

An object of the present invention is the provision of an improved operating valve arranged through the movement of a single part thereof to successively limit at the valve the volume of air used both for the clean-out blast and the sanding operation blast.

An added object of the invention is the provision of an improved arrangement of piping and valves in a sanding mechanism thereby eliminating numerous sections of pipes or a number of valves heretofore required.

Another object of the present invention is the provision of an improved operating valve having orifices of different sizes to effect different operations of a sanding mechanism.

A still further object of the invention is the provision, in a sanding mechanism, of the removal of an operating valve from a sand trap thereby simplifying the construction of the sand trap.

A further object of the present invention is the provision of an improved operating valve having double ports each leading to a sand trap and a plurality of orifices for admitting both clean-out and sanding operation blasts to each of the double ports.

The above and numerous other objects of the present invention will become apparent to those skilled in the art by referring to the accompanying drawings, wherein:

Figure 1 is a schematic view of a sanding mechanism embodying the present invention.

Figure 2 is a vertical sectional view of an operating valve adapted for use in a sanding mechanism.

Figure 3 is a vertical sectional view of a modification of the operating valve shown in Figure 2.

Referring now in detail to the drawing, wherein like reference characters indicate like parts, the numeral 1 is employed to designate, in a somewhat general manner, an illustrative sanding mechanism designed to be employed in diesel engines for railroads but of course need not be so limited. The usual wheel arrangement for wheels of the engine types comprises a plurality of pairs of drivers 2 and 3, 4 and 5. Each pair of drivers is provided with a set of sand traps 2a, 3a, 4a and 5a having sand supplied thereto from a source of supply (not shown) and suitable conduits 6 leading therefrom to convey sand to the

2

rails 7 adjacent to the respective drivers. The sand traps may, if desired, be in accordance with the teachings of my patent application Serial No. 709,224, filed November 12, 1946, now abandoned, because such sand traps are now being currently used in a mechanism of the present invention.

Joining related sand traps is a fluid pressure supply line 2b, 3b, 4b and 5b with each line having interposed therein between its ends an operating valve 2c, 3c, 4c and 5c. The operating valve is shown in cross-section and more detail in Figures 2 and 3 of the drawing and is to be considered more in detail hereinafter but for the present it is deemed more advisable to continue with a complete description of the circuit and components of the sanding mechanism. The operating valves related with the supply lines 2b and 3b and the operating valves related with the supply lines 4b and 5b are joined or connected together by fluid pressure actuating lines 8 and 9 respectively so that when fluid pressure is sent through the actuating line 8 the drivers 2 and 3 will be sanded in a forward direction and when fluid pressure is sent through the actuating line 9 the drivers 4 and 5 will be sanded in a back-up direction. Removed from the arrangement thus far described is a control valve 10 having leading therefrom a pair of feed lines 8a and 9a which communicate with the actuating lines 8 and 9 respectively so that upon a proper manipulation of the control valve, which is in direct communication with a reservoir of fluid pressure, fluid pressure can be delivered to either of the feed lines.

All of the above has been more or less of a suitable background for a proper understanding of the purpose and mechanics of the operating valve which actually forms the basis for the present application. Accordingly, by referring now to Figure 2 particularly the operating valve, of which four in number are employed in the illustrative arrangement of Figure 1, comprises a casing or housing 11 having an upper enlarged cylindrical head piece 12 and a relatively smaller lower cylindrical tail piece 13. Threadably mounted on the head piece is a cap or closure member 14 being suitably apertured for the reception of an end of the actuating lines 8 or 9 and for the introduction or admission of fluid pressure to the related port of the casing. Formed in an upper part of the head piece is a cylindrical wall 14 opening upwardly toward the cap. Disposed within the cylindrical wall is a main piston head 15 of a compound or differential valve member 16 with the main piston car-

rying a suitable gasket or cap 17 to arrest the passage of fluid pressure therebeyond. The tail piece 13 is provided with a cylindrical cavity 18 which is closed at one end by a removable plug 19 which may be provided with a sealing ring 20 interposed between the plug and casing to form a leak-proof joint therebetween. Positioned at one end of the cylindrical cavity is a relatively small or auxiliary valve head 21 arranged to normally bear against a valve seat 22 formed in the casing and facing toward the cavity to present a bearing area against which the auxiliary valve head may rest to, during certain operating conditions, prevent the passage of fluid pressure from the cavity beyond the auxiliary valve head.

Outstanding from the auxiliary valve head, axially of the valve is a shank 23 having at its free end a spring plate 24 arranged to move freely within the cylindrical cavity. Interposed between the spring plate and the plug 19 is a compressible element or coil or helical spring 25 arranged to allow the valve to move in a direction toward the plug as well as augment the action of the fluid pressure against the exposed face of the auxiliary head during certain operations of the valve. An inlet port 26 is provided in the tail piece to be in communication with the cavity 18 and this port has associated therewith a conduit 27 (see Figure 1) which is in direct communication with a constant source of fluid pressure supply preferably, the main reservoir. In this manner the cavity is at all times charged with fluid pressure for the purpose to be made hereinafter apparent.

Between the cylinder cavity 14 and cylindrical cavity 18 the casing is formed with a somewhat stepped cylindrical interior chamber 29 for the accommodation of a valve stem 30. The valve stem is purposely and desirably formed of different cross-sectional area and thereby presenting a guiding or relatively large base 31 merging with a spacer or relatively small neck 32. As indicated above, the base 31 is guidingly received by the casing to define the path along which the valve member will travel in service. The valve stem, preferably joining integrally the main piston and auxiliary head, is arranged during certain operations to slide axially of the casing and since the shouldered lower part of the casing presents a sloping or frusto-conical seat 33 which may hereinafter be termed the stem seat, the stem base is arranged to come to rest against the stem seat to limit the movement of the valve and cut off the passage of fluid pressure beyond the plane of the valve seat.

Spaced on opposite sides of the stem and at a location between the piston chamber 15 and the cylindrical cavity 18, are a pair of chambers 34 arranged to communicate directly through suitable ports 35 with the supply lines 2b, 3b, 4b or 5b depending upon the particular location of the operating valve in the arrangement (see Figure 1). These chambers which are desirably cored in the casing, each have leading therefrom to the interior of the casing a relatively large orifice or opening 36 which may be hereinafter termed the clean-out blast opening or orifice. These clean-out blast orifices are preferably and intentionally located to one side of the valve stem seat so that as the stem comes to rest against its seat fluid pressure will be cut off from the clean-out blast orifices. Disposed adjacent to the clean-out blast orifices are drillings or cored relatively smaller orifices 37 also diametrically

disposed and leading to the interior of the casing. These smaller orifices are provided with plugs or screws 38 each of which have formed therein, cross ports or drillings 39 so that a restricted amount of fluid pressure may pass from the interior of the casing, through the smaller orifices and cross drillings into the related chamber to find its way to the fluid pressure supply lines 2b, 3b, 4b or 5b to effect a sanding operation.

The operation of the thus described arrangement is as follows: If it is desired to sand before the drivers 2 and 3 the operator will shift the control valve so as to permit fluid pressure to pass from the source of supply through the feed line 8a to the actuating line 8 and enter the piston cavities 15. This pressure against the piston or valve head 15 will cause the valve to move downwardly, the area of the piston 15 times the pressure being sufficient to cause a positive movement of the auxiliary valve head 21. As soon as the auxiliary valve heads are unseated the fluid pressure within the cavity 18 will pass therebeyond to surge into the chambers through the orifices and thus to the supply lines 2b and 3b. This temporary or limited surge of fluid pressure will enter the sand traps to effect a clean-out operation and will continue until the stem base comes to rest upon its seat. At this time fluid pressure will be cut off from the clean-out blast orifices leaving only the small openings and cross drillings for the passage of fluid pressure into the chambers. This restriction in the flow of fluid pressure will effect a sanding operation which of course will carry sand out of the traps 2a and 3a through the related conduits 6 on to the rails adjacent to and forwardly of the forward drivers. As soon as the control valve is manipulated to cut off the fluid pressure from the actuating line 8 and this line is bled, the pressure against the auxiliary head 21 will again seat the auxiliary head on its seat 22. The upward movement of the valve member opening the ports 36 and permitting a clean-out blast to be transmitted to the sand traps. As will be appreciated, the part of the mechanism for sanding before the back-up drivers is brought into play by a like manner only in this case the control valve is manipulated so as to charge the feed line 9a and actuating line 9.

By referring now in detail to Figure 3 of the drawing it will be noted that this modification of the operating valve is substantially identical with the operating valve shown in Figure 2 and described in detail hereinabove excepting that the screws 38 of the previously described construction are dispensed with and the casing is formed with a pair of small orifices or drillings 40 leading directly from the interior 41 of the casing to the chambers 42 to effect a sanding operation. This casing is further provided with solid plugs 43 which prevent the escape of fluid pressure from the chambers through the tapped plug accommodating openings 44. These latter openings serve two functions, one, for the insertion of a tool to form the orifices 40 and two, to allow clean-out of openings 40 if same should become clogged by pipe scale or other foreign matter.

From the above it will be noted that various alterations and changes may be made to the illustrated and described construction without departing from the spirit of the present invention and scope of the appended claims.

I claim:

1. In an operating valve for use in a sanding mechanism, the combination of, a casing, a valve

member within said casing and provided with a large and a small head, said small head being arranged to be displaced from normal position away from a seat to admit the compressed fluid into the space between the lowermost head and the adjacent stem of the valve member, a stem of different cross-section connecting said heads, a chamber in said casing, an outlet leading from said chamber to the exterior of said casing, orifices of different size leading from adjacent said stem to said chamber, and a face of said valve member adjacent the stem thereof being arranged to contact a seat to cut off communication to one of said orifices.

2. In an operating valve for use in a sanding mechanism, the combination of, a casing, a valve member within said casing and provided with a large and a small head, a spring acting against said small head and the latter being arranged to be displaced from normal position away from a seat to admit fluid pressure therebeyond, a stem connecting said heads, a chamber in said casing intermediate said valve heads, an outlet communicating with said chamber, and orifices of different size leading from an interior of said casing to said chamber, another face of said valve member being arranged to contact another seat to cut off communication to one set of said orifices.

3. In an operating valve for use in a sanding mechanism, the combination of, a casing, a valve member within said casing and provided with a large and a small head, said casing having a chamber therein intermediate said valve heads, a spring acting against said small head and the latter being arranged to be displaced from normal position away from a normally engaged seat to admit fluid pressure into said chamber, a stem connecting said heads a portion of said stem being adapted to contact a seat to cut off the flow of fluid past said portion, an outlet communicating with said chamber, an orifice leading from the interior of said casing into said chamber, a second orifice spaced from said first named orifice and a removable plug carrying an orifice smaller than said first named orifice and entering said second named orifice and leading from said interior of said casing into said chamber, and an enlarged portion on said stem arranged to contact another seat to cut off passage of fluid pressure through said first named orifice.

4. In an operating valve for use in a sanding mechanism, the combination of, a casing, a valve member within said casing and provided with a large and a small head, a stem provided with portions of different cross-section connecting said heads, one of said portions forming a guide for said valve, a chamber in said casing intermediate said heads, a port leading from said chamber, an orifice connecting said chamber and an interior of said casing, an orifice smaller than said first named orifice, and said second named orifice formed as a drilling in said casing and connecting said chamber and said casing interior; said stem being arranged to slide in said casing and allow the fluid to pass beyond said small valve head to the casing interior and through both orifices; said stem being further arranged on further movement in the same direction to cut off the flow of fluid pressure through said first named orifice.

5. In an operating valve for use in a sanding mechanism, the combination of, a casing, a valve member within said casing and provided with a large and a small head, a stem joining said heads

and having a shouldered portion intermediate its ends, oppositely disposed exhaust ports in said casing, oppositely disposed chambers in said casing leading to said exhaust ports, oppositely directed orifices leading from an interior of said casing into said chambers, oppositely directed restricted orifices leading from said casing interior into said chambers, and a seat formed in said casing between said first and second named orifices; said small head being arranged to be displaced from a seat to permit the passage of fluid pressure therebeyond through all of said orifices; chambers and ports, and said shouldered stem being arranged to contact said first named seat for arresting the flow of fluid pressure through said first named orifices.

6. In an operating valve for use in a sanding mechanism, the combination of, a casing, a valve member within said casing and provided with a large and a small head, a spring acting against said small head, a stem joining said heads and having a shouldered portion intermediate said heads, ports in said casing, chambers in said casing leading to said ports, orifices leading from an interior of said casing into said chambers, restricted orifices leading from said casing interior into said chambers, and a seat formed in said casing between said first and second named orifices; said small head being arranged to be displaced from a second seat from normal position to permit the passage of fluid pressure therebeyond through all of said orifices, chambers and ports, and said shouldered stem being arranged to contact said first named seat for arresting the flow of fluid pressure through said first named orifices.

7. In an operating valve member for use in railway sanding mechanism, the combination of, a casing, a differential valve within said casing, a piston stem interposed between the ends of said valve, a clean-out orifice adjacent said stem and adapted to be closed by a movement of said stem in one direction against a seat, and means adjacent said stem to permit a limited flow of air for sanding through another orifice when said clean-out orifice is closed.

8. In an operating valve for use in a railway sanding mechanism, the combination of, a casing, a plurality of outlets in said casing, an intake opening within said casing, a differential valve member within said casing adapted, upon movement of said valve in one direction, to provide for admission of air to each of said outlets, and means within said casing for limiting the flow of admitted air to each of said outlets when said valve has completed its movement in one direction.

9. In a sanding mechanism, the combination of, an operating valve, a single air line leading from said operating valve for effecting a clean-out blast and a sanding operation of air to a sand trap in a valve member, an inlet port in said valve member for admission of a constant source of air pressure, a clean-out blast orifice and a restricted sanding orifice in said valve member and communicating with said constant source of pressure, and a differential valve head in said valve member for selectively allowing air to pass through both orifices during movement of said differential valve away from one valve seat from normal position and allowing air to pass through only said restricted sanding orifice while contacting another valve seat when said differential valve has reached the end of its travel from normal position.

10. An operating valve for use in a sanding mechanism, the combination of, a casing, a valve member movably mounted within said casing, said member comprising two valve heads of different diameters and a third head depending from the smaller of said first named heads, a seat for said third head, a clean-out blast orifice in said casing and a restricted opening leading from said casing into said orifice, the initial movement of said valve member in one direction causing a simultaneous opening of said orifice and said restricted opening to admit fluid pressure thereto, the subsequent movement of said member closing said orifice, and means for causing said fluid pressure to flow through said restricted opening.

11. In a fluid operating valve, the combination of, a casing, a valve member within said casing and provided with a large and small piston heads, a stem connecting said heads to form said valve member, said casing having an orifice adjacent the space intermediate said heads, means for admitting fluid pressure to one side of said

5

large piston head to move the same in one direction, fluid pressure means reacting against said small head at all times, said head permitting the passage of fluid pressure to said orifice when said head is moved from normal position, and means carried by said stem adapted upon movement of said valve member to close said orifice.
